TUBA CHAIR

Jerry A. Wenger, Owatonna, Harvey M. Urch, West Concord, and Lenard W. Nordman, Owatonna, Minn., assignors to Harry J. Wenger, Owatonna, Minn.

Filed June 17, 1965, Ser. No. 464,696
10 Claims. (Cl. 297—186)

The present invention relates to an improvement in a combination chair and musical instrument support. More specifically the present invention relates to a combination chair and support for a class or type of larger horn known generally as a tuba. Briefly the structure comprises an elongated frame having at one end a vertical chair support and at the other a corresponding instrument support. The chair is both slidably and rotatably secured to the vertical chair support. A musical instrument gripping device is adjustably secured to its support for establishing the proper attitude of the instrument. Particularly novel are the channel and slotted plate locking means that is foam plastic biased against a slot engaging tongue to give quick adjustment and positive holding of the instrument gripping device in a given position.

In many musical organizations, such as are found in schools, the musicians are often relatively young and small, lacking in the strength to support a large instrument such as a tuba and thus the need for a support for such an instrument is particularly critical. It is also widely recognized that most damage to an instrument results not when the instrument is being played, but rather when the instrument is set aside or lying around. Thus it is particularly desirable to provide an instrument support to accommodate the different sizes of tubas to avoid these negligent injuries. In these same organizations the instrument is generally owned by the schools and may be used by several students at different times and thus the instrument support should be readily adjustable to accommodate a plurality of musicians. It is desirable, nevertheless, to allow the instrument to remain in a satisfactorily adjusted position during breaks and the like while allowing a musician to extricate himself without performing complicated gymnastics, from the chair of the combination without disturbing adjustment of the instrument. This is the problem that the prior art has not solved.

It is an object of the present invention to provide a combination chair and musical instrument support which will accommodate both musicians and tubas of various sizes.

It is a further object of the present invention to provide a combination chair and musical instrument support which will allow the musician to easily extricate himself from the device without disturbing the adjustment of the instrument.

It is still a further object of this invention to provide means for holding adjustments of the musical instrument support once made.

It is yet a still further object of this invention to provide a chair which is slidably and rotatably secured to the unit so that a musician may easily extricate himself from the combination by sliding backward and pivoting.

It is still yet a further object of this invention to provide a combination chair and tuba support which is comprised of: an elongated frame, adapted to sit firmly on a platform or other flat surface; said frame having, rigidly secured to its rear end, a vertical chair support; a chair which is both slidably, fore and aft, and rotatably, about a vertical axis, secured to said vertical chair support; and a musical instrument support adjustably secured to the forward end of said elongated frame, said musical instrument support being vertically adjustable and pivotable in any direction so as to provide pivotable adjust-

2

ment about a plurality of axes. The actual instrument gripping member is fully adjustable to accommodate a wide range of sizes of instruments with a new and unique locking method comprising: a lipped channel member adapted to slide within a tube member; an elongated slotted plate member transversely movably secured to said channel on its inside member and retainer therein by said channel's lips; resilient means for urging the elongated plate member into engagement with the channel's lips; and a locking lip on said tube to engage the slots of the elongated plate member.

Other objects of the invention will become apparent as the description proceeds.

To the accomplishment of the foregoing and related ends, this invention when comprises the features herein-after fully described and particularly pointed out in the claims, the following description setting forth in detail certain illustrative embodiments of the invention, these being indicative, however, of but a few of the various ways in which the principles of the invention may be employed.

The invention is illustrated by the accompanying drawings in which the same numerals refer to corresponding parts and in which:

25 FIGURE 1 is a side elevation of the combination chair and instrument support;

FIGURE 2 is an end view looking from the right in

FIGURE 1 and drawn to the same scale as FIGURE 1;

FIGURE 3 is an enlarged side view in partial section

30 of the instrument support portion of the device drawn to a larger scale than in FIGURE 1;

FIGURE 4 is a section taken on the line and in the direction of the arrows 4—4 in FIGURE 3 and is drawn to a larger scale than FIGURE 3;

35 FIGURE 5 is a section taken on the line and in the direction of the arrows 5—5 in FIGURE 3, and is drawn to a larger scale than FIGURE 3;

FIGURE 6 is a top and fragmentary sectional view

40 of the instrument support portion of the device and is drawn to a larger scale than FIGURE 1;

FIGURE 7 is a view of the instrument support mem-

ber in the instrument support bracket and the instrument

support bracket in the direction of the arrows 7—7 in

FIGURE 6 and is drawn to the same scale as FIGURE 6;

45 FIGURE 8 is a sectional view taken in the direction

of the arrows 8—8 of FIGURE 7;

FIGURE 9 is a section taken along the line and in

the direction of the arrows 9—9 of FIGURE 3, and is

drawn to a larger scale than FIGURE 3;

50 FIGURE 10 is a view taken along the line 10—10 of

FIGURE 1, and is drawn to a larger scale than FIG-

URE 1;

FIGURE 11 is a view taken along the line 11—11

55 of FIGURE 10, and drawn to the same scale as FIG-

URE 10; and

FIGURE 12 is a view in the direction of the line 12—12

in FIGURE 1, and drawn to a larger scale than FIG-

URE 1.

60 In FIGURES 1 through 12, a frame 21 is adapted to

stand firmly on a flat surface by means of suitable legs

as at 22 and 23. A vertical chair support 24 is rigidly

secured to the rear end of the frame 21. The channel

65 25 is rigidly secured to the vertical chair support 24 by

any suitable means, as for example, by welding. It is

desirable to provide chair support brackets 26 as a

convenient means for lending greater support to the chan-

nel 25. The chair support brackets 26 are desirably

formed of plate stock and are rigidly secured to both

the vertical member 24 and the channel 25.

70 At the forward end of the channel 25 a plate 27 is

rigidly secured which acts as a stop to limit the forward

sliding motion of the chair 40. The plate 27 may be

rigidly fixed to channel 25 by any suitable method as by welding. At the rear end of the channel 25 it is desirable to provide a removable stop to limit the rearward sliding of the chair 40 but which will allow the chair 40 to be removed. One way of accomplishing this is by the use of the angle 28 which is removably secured to the channel 25 by any functional means as by the screw and wing nut assembly 29.

An inverted channel 30 slidably embracing the channel 25 has a web 32 from which the flanges 34 depend and serve to support the lips 31 extending inwardly parallel to the web 32. The channel 30 is wider than the channel 25 so that there is space between the flanges 34 of the channel 30 and the corresponding flanges 33 of the channel 25. The spaces between the flanges 34 and the flanges 33 are, in the preferred configuration, taken up with the resilient angles 35. The resilient angles 35 are desirably rigidly secured to the channel 30 and disposed in such a manner so that one of the legs of each of the angles 35 is disposed in each space between the channel flanges 33 and 34. Angles 35 can be constructed of any firm, resilient material, but are desirably a plastic which has lubricating qualities. One illustrative method of securing the angles 35 to the channel 30 is to thread the cap screws 36 through the angles 35 and channel 30 to the lower bearing plate 37 which is to be rigidly secured to the channel 30. An upper bearing plate 38 is provided and desirably rides on the ball bearings 39 and is rotatably secured to the lower bearing plate 37.

A chair 40 comprised of a back rest 41 and seat 42 is rigidly secured to the upper bearing plate 39. Thus, it will be seen that a chair 40 is provided which can slide fore and aft and which can be rotated about a vertical axis.

The forward end of the frame 21 is desirably formed of a hollow, vertical standard 50. While the vertical standard 50 may be of any suitable shape, a square or rectangular cross-section has been found to be very practical.

A vertical post 51 is provided, with such dimensions as will allow it to be inserted into the vertical standard 50 with a sliding fit so as to provide for a vertical adjustment therebetween. Means are provided for preventing relative motion between the vertical standard 50 and the vertical post 51. One convenient way of doing so is by the locking provision, as is best depicted in FIGURE 12, wherein a collar 52 is formed with similar dimensions to the vertical standard 50 except that it is not closed. One side of the collar 52 is open with flanges 53 and 54 extending parallel to one another from one side of the collar 52. It has been found convenient to provide a threaded plate 55 which is rigidly secured to the flange 53 by any suitable means as for example by welding. Threaded into the plate 55 is a threaded rod at 56 which is adapted to draw the flanges 53 and 54 together, thus clamping the collar 52 tightly in position. The threaded rod 56 has, rigidly secured at its one end, a handle 57 which is prevented from contacting the collar flange 54 by a washer 58. Threaded rod 56 is inserted through the holes 59 and 60 in the collar flanges 54 and 53, respectively, and threaded into the threaded hole in the plate 55. A retaining ring 61 is permanently affixed to the end of the threaded shaft 56 to prevent the unit from being lost.

At the upper extremity of the vertical post 51 a horizontal arm 62 is provided. The horizontal arm 62 is disposed rearwardly along the axis of the elongated frame 21.

A bracket 63 is pivotably secured to the horizontal arm 62 about a horizontal axis transverse to the axis of the elongated frame 21. The pivoting may be accomplished in any convenient manner as by the use of the nut and bolt assembly 64. Plate 65 is rigidly secured between the sides 66 and 67 of the bracket 63. The plate 65 may be so secured by any suitable means which will provide a rigid unit, as for example, by welding. A threaded hole 68

is provided in the plate 65 and is disposed immediately above the horizontal arm 62. The threaded shaft 69 has a knob 70 rigidly secured to its one end. Threaded shaft 69 is screwed into the threaded hole 68 of the plate 65. The end 71 of the threaded shaft 69 bears upon the upper surface of the horizontal arm 62 thus providing means for making a pivot adjustment about the axis of bolt 64 by screwing in or out the threaded shaft 69.

A spacing block 72 is rigidly secured to the end of the bracket 63 by any suitable means, as by welding. The hole 73 is provided in the spacing block 72.

A universal joint 74 is pivotably secured to the bracket 63. It is desirable to provide a mode of securement which will hold an adjustment once made. Exemplary of such securements is providing a yoke 75 on the universal joint 74 of a larger dimension than the spacing block 72. The resulting gap between the spacing block 72 and the yoke 75 is taken up with friction washers, as for example the fiber washers 76, and a bolt 77 is used as an axis. The bolt 77 is held in place by the nut 78 which is tightened so as to compress the fiber washers 76 thus providing the proper friction joint. It is apparent that the instrument gripping member may be pivoted by manually overriding of the friction in the joint. Unless purposely moved, however, the joint will hold its position because of the friction. The universal joint 74 is of a type well-known in the art, adapted to be non-rotating while an instrument is being played. The tubular arm 79 forms a rotatably secured portion of the universal joint 74 and is secured thereto by the bolt 80 which forms the axis of rotation thereof. It is desirable to introduce a friction member into this joint so that an adjustment, once made, will be retained. A suitable friction member is demonstrated by the fiber washers 73 which are interposed between the tube 79 and the yoke 75 of the universal joint 74. The bolt 80 serves as a pivot axis for the tube 79 and is retained by the nut 81 which is tightened so as to compress the fiber washers 73 thus providing the proper friction joint. It is obvious that the instrument gripping means can be pivoted about the axis of the bolt 80 by manually overriding the friction in the joint. Once an adjustment has been completed, however, and the force released, the friction will hold the instrument in position.

A second tubular structure 82 similar to the tube 79 is rigidly secured thereto at right angles to the tube 79 and extending downward. The tubular structure 82 has, at its lower extremity, a lip 83 at the entry into said tube 82. A built-up male member 84 is of such dimensions as to fit slidably in the tube 82. The built-up male tube is desirably constructed of a channel 84a with lips 85 extending inwardly from the flanges 86 and parallel to the web 87 of said channel 84a.

A tongue 88 is rigidly secured to the upper end of the male tube member 84. The tongue 88 should be of the largest length dimension which will allow a free sliding fit of the male member into the tube 82. An inspection of FIGURE 3 will make it readily apparent that the male member 84 cannot accidentally drop from the tube 82 since the tongue 88 will, if the tubes are pulled apart without the locking means being engaged, catch on the lip 83 preventing accidental separation of these items. The male member 84 may, however, be separated from the tube 82 by moving the tube 84 in the direction of the lip 83 thus pivoting the tongue 88 upward allowing it to be slipped out of the tube 82. An elongated plate member 89, of a width greater than the opening between the lips 85 of the channel 84a, is loosely secured to the tongue 88 so that the plate member 89 may be slid over the entire length of the tongue 88. A convenient method for accomplishing the aforementioned loose securement of the plate 89 to the tongue 88 is to provide a transverse slot 90 in the plate 89 of such dimensions that will loosely depend from the tongue 88. The plate 89 is disposed within the interior of the channel 84a thus being retained therein by the lips 85. A plurality of

regularly spaced slots 91 transverse to the plate 89 are provided therein and are of such dimensions as to allow engagement with the lip 83. It is necessary to resiliently urge the plate 89 against the interior of the lips 85 over the full length of the plate 89. While any type of resilient member that will accomplish the aforementioned end may be used, one very desirable means is illustrated by the use of a resilient plastic foam filling for the cavity or interior of the tube 84.

It will be readily observed that an adjustment may be made, changing the relative positions of the tube 82 to the tube 84, by depressing the plate 89 at its lower end against the urging of the resilient foam filler 92. Such depressing disengages the lip 83 from the slot 91. The tube 84 is then moved either up or down, relative to the tube 82 until it is at the desired position at which time the plate 89 is released and is resiliently urged toward engagement with the lips 85. As slot 91 of the plate 89 is placed in engagement with the lip 83, the tubes 82 and 84 are locked to one another.

At its lower end, the channel 84 is desirably bent rearwardly to provide a lower instrument support arm. A plate 93 is rigidly secured to the channel 84a between the flanges 86 thereof, by any suitable means, thus forming a slot 93a. The lower instrument gripping member 94 is comprised of the pads 95 and 96 which are rigidly secured to the bracket 97. Pads 95 and 96 are disposed so as to securely seat and grip the base of the instrument intended to be held by said gripping member 94. A tongue member 98 is rigidly secured to the bracket 97. The tongue 98 is desirably of a width dimension which approximates the opening between the lips 85 of the channel 84a. Thus, to insert a lower instrument gripping member 94 one merely places the tongue 98 pointed rearwardly between the lips 85 of the channel 84a and slides the gripping member 94 rearwardly until the tongue 98 is retained by the plate 93 in the slot 93a. The instrument gripping member 94 is locked in place by means of a pin 99. The pin 99 may take the form of a bolt and nut or any other releasable pin. One convenient pin, however, is a sheet metal screw.

Both halves of the tube 79, viz, the portions on each side of the pivot 80, are identical as are the pieces associated therewith thus only one side will be hereafter described in detail.

A tube 100, of such dimensions as to be readily slideable within the tube 79, is provided. The male-female joint between the tubes 100 and 79 is the same as the vertical joint between the tubes 82 and 84 with the exception that the instant joint is disposed horizontally. The tube 100 is of built-up construction similar to that of the lower support tube 84. The extremity of each of the tubes 79 is formed as a lip 101 closing off part of the interior of the tube 79. The extremity of the tube 100, which fits into the tube 79, is formed as a tongue 102, of the largest length dimension which will permit a sliding fit with the tube 79. It is thus apparent, from an examination of FIGURE 6, that if the tube 100 is pulled out of the tube 79 to almost its full length that the tongue 102 will interfere and catch on the lip 101 preventing an inadvertent separation of the tubes 79 and 100. It is also apparent that if it is desired to separate the tubes 79 and 100 one merely must move the tube 100 toward the lip 101 which allows the tongue 102 to slide free of the lip 101 and the tubes 100 and 79 to be separated.

The tube 100 is desirably formed of a channel 100a with a web 103, flanges 104 and inwardly directed lips 105 depending from the flanges 104 and parallel to the web 103. An elongated plate 106 is loosely secured to the tongues 102 and 79 so that the plate 106 may be moved along the full length of the tongue 102. One convenient way of accomplishing the aforementioned loose securing of the plate 106 to the tongue 102 is to provide a transverse slot 107 in the plate 106. The

slot 107 being of such dimensions as will allow free sliding of the plate 106 on the tongue 102. A plurality of regularly spaced transverse slots 108 are provided in the plate 106. The slots 108 are of such dimensions as to be able to engage the lip 101 of the tube 79. Plate 106 is disposed on the interior side of the lips 105 of the tube member 100. Said plate 106 being of a width dimension which is greater than the distance between the lips 105. Thus, it is apparent that the lips 105 will retain the plate 106 within the interior of the tube 100. Resilient means are provided to urge the plate 106, uniformly along its full length, against the lip 105 of the channel 100a. Said resilient means may be of any suitable type which will accomplish this end, but a very desirable and convenient means is provided by filling the interior of the tube with a resilient plastic foam 109.

It is obvious that to extend or decrease the length of the instrument support arms the plate 106 is depressed at its exposed end. Slot 108 is thus freed from engagement with the lip 101 leaving the tubes 100 and 79 in an unlocked relation. The tube 100 is then either slid into or is withdrawn from the tube 79 to the desired position. The resilient material 109 will resiliently urge the plate back to a position against the lips 105 when the pressure on the plate 106 is released. A slot 108, when engaged by the lip 101, will lock the tubes 79 and 100 in rigid relative relation to one another.

The tube 100 has, at its opposite end and rearwardly disposed, an instrument support arm. A plate 110 is rigidly secured between the flanges 104 of the channel 100a in the instrument support arm by any suitable means as for example by welding thus forming the slot 111. The musical instrument gripping member 112 is comprised of pads 113 and 114 which are rigidly secured to the bracket 115. A tongue member 116 is rigidly secured to the bracket 115. Said tongue member 116 is of such a thickness so as to form a firm sliding fit between the web 103 and the plate 110 in the slot 111 and of a width which just allows it to pass through the opening between the lips 103 of the channel 100a. The instrument gripping member 112 is retained in position by providing a pin 117 to prevent sliding of the tongue 116 out of the slot 111. The pin 117 may take the form of a nut and bolt or any other readily movable pin type fastener. One very convenient pin 117, however, is a sheet metal screw.

It will be noted that it is very convenient, from a manufacturing point of view, to provide that the male members 84 and 100 are interchangeable. Thus, in any unit sold, three members 84 will be provided keeping a replacement inventory to a minimum and preventing possible confusion and mixing of non-interchangeable parts in the packing of the original unit.

It will be noted that three dimensional pivotable adjustments of the instruments are available via pivoting universal joints. A vertical adjustment is accomplished by raising or lowering the vertical post 50 within the vertical standard 51 and locking it in position with the collar 52 and clamping mechanism provided thereon. The instrument once clamped into the instrument support may be tilted to and from the musician by turning a knob 71 one way or the other. The instrument may be given a yaw adjustment by pivoting the instrument about the bolt 77, as is desired; the adjustment being held by the friction member 76 in this joint. A list, or sideway tilt to either side may be accomplished by pivoting the instrument support about the bolt 80, the adjustment, once made, is held by the fiber friction washers 73. The instrument gripping members 94 and 112 having been adjusted so as to firmly clamp and hold the tuba to be used.

It is thus obvious that a new and very useful combination chair and tuba support which is fully adjustable to accommodate tubas and musicians of various sizes is herein described.

It is apparent that many modifications and variations of this invention as hereinbefore set forth may be made

without departing from the spirit and scope thereof. The specific embodiments described are given by way of example only and the invention is limited only by the terms of the appended claims.

What is claimed is:

1. A combination chair and musical instrument support stand comprising; an elongated frame adapted to stand on a platform; a vertical member located at the rear of and secured to said frame; chair support means longitudinally slidably secured to said vertical member; a chair member pivotally secured to said chair support means about a vertical axis; a hollow standard secured at the front of and to said frame; a vertical post member slidably secured to said hollow standard; locking means to prevent relative movement between said vertical post member and said hollow standard; a horizontal arm secured to said vertical post member and disposed longitudinally rearward along said frame's axis; a bracket member pivotally secured to said horizontal arm about a transverse horizontal axis; means for pivoting and holding said bracket member; a universal joint pivotally secured to said bracket about an axis perpendicular to the axis about which said bracket is pivoted; friction means for holding the adjustment of each pivot of said universal joint; a horizontal female member pivoted to said universal joint; a vertical female member rigidly secured to and depending from said horizontal female member intermediate the ends thereof; a vertical male member slidably within said vertical female member; means for selectively preventing said vertical male member from sliding relative to said vertical female member; an instrument support member secured to said male member and disposed longitudinally rearward; an instrument gripping member removably secured to said instrument support member; horizontal male members slidably received in said horizontal female arm member at the ends thereof; means for selectively preventing relative motion between said horizontal male and female arm members; an instrument support member rearwardly disposed and secured to the extremity of each of said horizontal male members and an instrument gripping member removably secured to each of said rearwardly disposed instrument support members.

2. The combination chair and musical instrument of claim 1 wherein the means for preventing said male members from sliding relatively to said female members comprises: a lipped channel member, an elongated plate member secured inside said lipped channel member as to be longitudinally practically immovable and transversely moveable to and from said lips, a plurality of longitudinally spaced transverse slots in said plate member, a tongue secured to said female member at its extremity and extending inwardly thereof to engage one of said slots of said plate member; and resilient means engaging said plate member and urging it against the lips of said lipped channel member uniformly.

3. The combination chair and musical instruments stand of claim 2 wherein the resilient means comprises a resilient foam material filling the interior of the male member, and a tongue secured to said lipped channel member; said elongated plate having an opening in it adjacent one end embracing the tongue of said lipped channel member.

4. A combination chair and musical instrument support comprising: an elongated frame adapted to rest on a flat surface, a vertical support member secured to said frame, a horizontal channel member rigidly secured to said vertical support member, plate chair support members rigidly secured to said vertical support and said horizontal channel member, an end plate rigidly secured to one end of said horizontal channel, a second end plate removably secured to the opposite end of said horizontal channel, an inverted channel with lips parallel to the web thereof and inwardly disposed, embracing, with a loose fit, said horizontal channel; resilient angle members secured to said inverted channel's web and disposed so as

to have one of said resilient angle's legs interposed in each gap between the flanges of said upright and inverted channels to fill said gaps; a lower bearing plate rigidly secured to the top of said inverted channel; a top bearing plate 5 rotatably secured to said lower bearing plate; a chair secured to said top bearing plate; a female vertical member secured to said elongated frame in spaced relation to said vertical support; a male vertical member slidably fitting into said female vertical member; means for preventing relative movement between said male and female vertical members; a horizontal arm secured to said male vertical member; a bracket member pivotally secured to said horizontal arm about a horizontal axis; means for pivoting said bracket member and holding said bracket in a 10 given position; a universal joint pivotally secured to said bracket about an axis perpendicular to said axis of the aforementioned bracket; means for preventing unintentional pivoting of said universal joints; a female arm member open at both ends pivotally secured near its 15 middle to said universal joint; a male arm member slidably secured in each end of said female arm member; means for selectively preventing relative motion between said male and female arm members; an instrument support arm secured to each of said male arm members and 20 extending horizontally therefrom; an instrument gripping member removably secured to each of said instrument support members; a female member depending from the mid-point of said female arm member; a male member slidably fitting in said depending female member; means 25 for selectively preventing relative movement between said depending male and female members; an instrument support arm rigidly secured to said depending male member and extending horizontally therefrom; and an instrument gripping member removably secured to said last mentioned instrument support arm.

5. The combination chair and musical instrument of claim 4 wherein the means for pivoting the bracket member and holding it in a given position comprises: a threaded shaft and means secured to said threaded shaft for 30 rotating it; said threaded shaft being threadably extended through said bracket perpendicular to the horizontal pivot thereof and bearing against a surface of said horizontal arm member.

6. The combination chair and musical instrument support of claim 4 wherein the means for preventing relative motion between said male and female members in each case comprises: an elongated plate longitudinally spaced with transverse slots therein, an elongated member 35 extending parallel to said plate and secured thereto against relative longitudinal movement while remaining free to move transversely relative thereto; a resilient member between said elongated member and plate urging them apart uniformly over the entire length of said plate, and an inwardly directed tongue member secured to said female member to engage the transverse slots of said elongated plate.

7. The combination chair and musical instrument support of claim 4 wherein there is a tongue member secured to each of said instrument gripping members and adapted to fit into a corresponding slot in the instrument support arm, and means engaging said instrument support arm and said tongue to prevent withdrawal of the latter from the former.

8. A combination chair and tuba support comprising: a frame; a chair secured to said frame to move longitudinally thereto; an instrument support secured to said frame spaced from said chair and vertically adjustable; and an instrument gripping means secured to said instrument support pivotally about a plurality of axes, said pivotal adjustment of said instrument gripping means comprising: a bracket pivoted about a horizontal axis to said instrument support, said instrument support including a bearing surface spaced from said horizontal axis; means movably secured to said bracket to move to and from said bracket and disposed opposite and engaging said bear-

ing surface; whereby actuating said movable means pushes a portion of said bracket away from and allows the same portion of said bracket to move toward said instrument support selectively to determine the attitude of said bracket relative to said instrument support about said horizontal axis, and means securing said instrument gripping means to said bracket.

9. A combination chair and tube support comprising: a frame; a chair secured to said frame to move longitudinally thereto; an instrument support secured to said frame spaced from said chair and vertically adjustable; and an adjustable instrument gripping means secured to said instrument support pivotally about a plurality of axes, said instrument gripping means including at least one male-female sliding joint, said female joint member comprising: a tube with a slot engaging lip rigidly secured to and inwardly disposed from the extremity thereof, said male member of said slide joint being comprised of, a lipped channel, an elongated plate embraced by said lipped channel and transversely movably secured thereto, said elongated plate being provided with a plurality of transverse slots therein said slots being adapted to engage the lip on said female joint member, and resilient means for uniformly biasing the plate member over its entire length toward the lips of said channel.

10. An adjustable sliding joint comprising, a tube with slot engaging lip rigidly secured to and inwardly disposed

at the extremity thereof, a male member of said slide joint comprising, a lipped channel, an elongated plate embraced by said lipped channel and transversely movably secured thereto, said elongated plate being provided with a plurality of transverse slots therein said slots being adapted to engage the lip on said female joint member, and resilient foam plastic filling said male slide joint member's interior for uniformly biasing the plate member over its entire length toward said channel's lips.
